UNITED STATES PATENT OFFICE

2,465,483

TOOL HANDLE FASTENER

Wesley J. Roberts, Hot Springs, Ark.

Application January 15, 1946, Serial No. 641,292

1 Claim. (Cl. 306—33)

1

This invention relates to a method of and means for securing a wooden shaft in a socket and more specifically to securing a wooden handle in the socket of a tool head. The invention may be applied to tools of various character, such as hammers, mallets, sledges, hatches, axes and the like, which comprise socketed heads secured to the end of a wooden shaft, the shaft serving as a handle.

It is an object of the invention to provide a device of the above character which may be utilized to secure the handle to the tool head firmly and permanently, and which permits of quick tightening should the handle become loose in the socket by reason of shrinkage of the wood.

The above and still further objects of the invention will be understood upon study of the following description, when taken in connection with the accompanying drawings, wherein like characters of reference denote the same parts throughout the several views, and wherein:

Figure 1 is an elevational view of a hammer employing the invention;

Figure 2 is an end view of Figure 1;

Figure 3 is a side view of a wedge forming part of the invention; and

Figure 4 illustrates half of an expanding bushing utilized as part of the invention.

Referring now to the drawings in detail, numeral 1 represents a hammer head, having a socket 2, within which may be inserted a wooden handle 3. The numeral 4 represents the head of the hammer and numeral 5 the claws thereof.

Formed within an end 6 of the hammer handle is a socket 7 of circular cross section within which is inserted the pair of expanding bushings 8, one of which is illustrated per se in Figure 4, and there denominated by the numeral 8. Each bushing half 8 is fabricated of metal, and has an inner groove 13 having the same radius of curvature as the conical wedging pin 9, and tapering to fit the said wedging pin snugly at all times. Formed integrally with and comprising the head of each bushing half 8 is a plurality of smaller radially outwardly-directed supplementary wedges 10, extending from the main body of the bushing and coming to points 11.

The wedging pin 9 tapers gradually, and comprises a circular head or cap 12 of larger diameter than that of the tapered portion and at its extremity opposite to the head 12 forms a sharp point 14, adapted to enter the wood of the handle 3 within the socket 7. The wedge halves are formed with recesses 13 adapted to accommodate the head 12 of the wedge pin 9.

The socket 7 and the bushing halves 8 are of such relative lengths that when the heads of the bushing halves are flush with the end of the handle 3, a small space 15 remains in the

socket 7 within which the wedge pin 9 may be accommodated should it be necessary, during the life of the tool and due to drying and contraction of the wood forming the handle 3, to increasingly force wedge pin 9 forwardly into the handle.

From the above description it should be obvious that the presently described embodiment of the invention provides a simple and inexpensive device capable, by means of a simple operation, of securing a handle to a tool head. The small auxiliary wedges 10 present a novel feature which catch the wood of the handle and assist in spreading the end of the handle, as well as to prevent rotation of the wedge halves 8 with respect to the handle 3.

Although I have shown and described a preferred embodiment of the invention, it is to be understood that modifications may be made in the arrangement of the parts and the details of the structure without departing from the spirit of the invention and within the scope of the appended claim.

What I claim is:

25 A fastener for securing tool handles in the heads thereof and wherein said handle is formed with a cylindrical end socket, comprising a pair of semi-cylindrical bushings adapted to be freely received in said socket, a substantially conical wedging pin, said bushings being formed with opposed inner grooves substantially complementary to said pin, said grooves and pin being formed with smooth abutting surfaces to adapt said pin to be driven between said bushings, whereby to wedgingly spread said bushings radially in opposite directions into firm engagement with the walls of said socket, and said bushings each being formed with a plurality of radially outwardly-directed supplementary wedges terminating in sharp points adapted to wedgingly seat in said handle upon spreading of said bushings.
